Treadwell

(10) **Patent No.:** **X7997**
(45) **Date of Patent:** **Feb. 5, 1834**

---

(54) **IMPROVEMENT IN THE ART OF ROPE
MAKING CALLED AN IRON TAIL**

(76) Inventor: **Daniel Treadwell**

HUG 1747505 ff
1830'sWhereas *James Franklin*,
a citizen of the United States, hath alleged that he has invented a new and useful improvement
in the art of *Boat-Making*, called *the Fair*,

which improvement he states has not been known or used before his application; hath, whereon to this, he does
verily declare that he is the true inventor or discoverer of the said improvement; hath paid into the treasury of the
United States the sum of thirty dollars, delivered a receipt for the same, and presented a petition to the Secretary
of State, signifying a desire of obtaining an exclusive property in the said improvement, and praying that a patent
may be granted for that purpose. These are therefore to grant according to law to the said *James Franklin*,
his heirs, administrators or assigns for the term of fourteen years, from the *first* day of *February*,
one thousand eight hundred and *thirty-four*, the full and exclusive right and liberty of making, constructing,
using and vending to others to be used the said improvement; a description whereof is given in the words of the said
invention, set forth in the schedule hereunto annexed and is made a part of these presents.

In Testimony whereof, I have caused these Letters to be made Patent and
the Seal of the United States to be hereunto affixed.

GIVEN under my hand at the City of Washington, this *first*
day of *February*, in the year of our Lord one thousand eight hundred
and *thirty-four*, and of the independence of the United States *an* *eighty*
the fifty-eighth.

BY THE PRESIDENT,

David W. Atchison
Secretary of State.

City of Washington, D. C.

I DO HEREBY CERTIFY That the foregoing Patent were delivered to me on the *first*
day of *February*, in the year of our Lord one thousand eight hundred and *thirty-four*,
to be examined; that I have examined the same and find them conformable to law, and I do hereby
return the same to the Secretary of State, within fifteen days from the date of my certificate,
this *first* day of *February*, in the year aforesaid.

The Schadels referred to in these Letters, Paley, and making
part of Mariana containing a description of the works of the said
Divine Master, & likewise of his biography in the art of hope
mentioning called *“Gran Tai”*.

Dear Mr. Daniel, the architect of Boston in
his Business and wealth of Massachussets Engineer he has invented a new
beautiful machine or instrument, in the manufacture of carriage & horses
vehicle machine or instrument is called an iron trail - This iron
trail is a substitute for the common ropes tails so called as such it is
according the use & object of which is well known to all workmen
either to hold in a stable, to tie, so that the proper quantity of iron may be
given without loss. - - - - - Complete drawings of the iron trail for which
a patent is now applied for, are enclosed, with these sketches determine
the extent of this specific invention.

Fig. 1 represents a view in front. Fig. 2, a plan. Fig. 3, a section.

The same letters refer to the same part in all the figures.

The drawings are for you to make a good estimated recipe.

A. A. is divided of wood or iron having this at the bottom of the
B. B. .... Face block CCCC one square inch on the side of the disk
A. .... Face cylindrical holes four from the center on each side of
the disk A. to the circumference one half of each hole being formed
at the center of the disk A. & the other banding half from the block
C.C. .... These holes are passed four iron or thin solid
wood DDDD and secured. The end of each of these, and block, and
the center of the disk is fastened with a screw having four
flat top and four cylindrical holes at the top when EEEE represent a section
of four streams of water and twisted together under the side the whoe
being covered by material of the nature of DDDD.

FFFF are being fired to the blocks CCC & the ring and
CCC & passing this line suitable for the purpose of adjusting the
expansions. B. It consists of two cables or ropes
each for the purpose of carrying the load at a given distance from
the top. The method of using them will be as follows. Having
bundled the strands of which the rope is to be formed, these are cut
until they lay as to be commenced are to be spayed twice the distance
between the ends of the cables. The top being then pulled with
sufficient degree of effort will be held by the rope
below the top. The load is then to be secured at a small distance
from the top by two cables passing from the hole CCC

top by the
steel. The numbers mentioned above are the same as
the early number of the letters above, and serve to indicate
the principal forms abounded by the strands, the ridge in the
center of each number falling into the junction of the ropes -

If the proportions be given for laying the
rope it will be found that as the rope advances the tail will
follow, continuing back until it does not turn around with
the rope - laying the strands smooth upon each other will
not rot the tail.

In the foregoing specification I have described the
tail as now constructed & used by me, various modifications
may be made in the different parts of this machine or structure
without departing from the character of my invention to be com-
mended in the construction & use of numbers formed of some solid
body. I declare they are capable of preserving their own figures
continuing them over which they pass to assume the figure
indicated by them.

In testimony of the above as a true specification
of my said invention I have this day set my hand at Boston
where and this twenty-third day of November Eighteen Hundred
and Thirty Three.
